UNITED STATES PATENT OFFICE.

JESSE P. SHORT, OF GREENSBURG, INDIANA.

RURAL MAIL BOX.

Application filed June 16, 1927. Serial No. 199,144.

My invention relates to improvements in mail boxes, and particularly that type adapted for rural free delivery service. It has for one of its object the provision of a money or coin receptacle attachment for placement in the box and of such construction as to enable the mail carrier to remove the money contents with a minimum expenditure of effort and time.

10 For the purpose of disclosing my invention I have illustrated one embodiment thereof in the accompanying drawing, in which,

Fig. 1 is a perspective view of a mail box embodying my invention;

15 Fig. 2 is a front elevation of the money receptacle and collection mail holder;

Fig. 3 is a plan view of the money receptacle attachment;

20 Fig. 4 is a sectional view on the line 4, 4 of Fig. 2;

Fig. 5 is a longitudinal sectional view of the money receptacle;

25 Fig. 6 is a perspective view of the money box holder;

Fig. 7 is a detail section showing the money slide bumper;

Fig. 8 is a detail section showing the means for locking the front end of the money drawer guide top to the body portion, and

30 Fig. 9 is a perspective view of the money drawer.

In the embodiment of my invention I provide a mail box 1 of the usual rural free delivery type having the rounded top and provided with a door 2 at its front to permit access thereto and with the usual signal flag 3.

35 The money receptacle is adapted to be placed within the box and suspended from the top thereof so as to leave the bottom part of 40 the box free for the insertion of delivery mail.

In constructing this receptacle I provide a guide and supporting member for the money drawer, which is preferably formed from a 45 single piece of sheet metal in which the metal is turned up vertically from the bottom 4 to provide vertical sides 5. The metal is then turned outwardly as at 6 and then bent slightly downwardly at 7 so that the parts 6 and 7 50 form supporting flanges, the flanges 7 being at such an angle as to conform substantially to the slope of the top of the box. This guide and supporting member is secured in position by means of bolts 8 which pass through the 55 top of the box and through the flanges 7. At the rear end of the bottom 4 the metal is slit

and struck up to form the upwardly extending tongue 9, the purpose of which will appear more fully hereinafter. The forward portion of the guide support for the money drawer is covered by a cover plate 10 which, at its rear end is provided, intermediate of its two sides, with a tongue 11 forming a guard for the return spring of the money drawer and on each side with a pair of extended 60 tongues 12 which increase the bearing surface of the cover plate on the flange portion 6. The front end of this cover plate is provided with a pair of forwardly extending tongues 13 which are turned over the forward edge of 70 the flanges 6 to secure the cover plate in position at the front and the cover plate, at its rear is secured in position by means of bolts 14 passing through the plate and the flanges 6. At each side of the tongue 11 the metal of 75 the plate 10 is bent downwardly at right angles to the plate to form the backing tongues 15 to which is secured, by means of bolts 16, bumpers 17.

The money drawer is preferably formed 80 from a single sheet of material, being bent up from the bottom 18 to form the sides 19, which side portions at their tops are again bent inwardly as at 20. These side portions at their forward ends have out-turned ears 85 21. The rear portion of the bottom 18 is bent upwardly as at 22 to form the back, and inwardly as at 23 to form a partial back cover. At the angle between the bottom 18 and the back 22 the metal is slit on parallel lines and 90 the material between these lines is slightly bent outwardly as at 24 to form a hook for the reception of the end of a coil spring. The money drawer fits within the guide member beneath the top plate 10 and is adapted to 95 slide back and forth, being drawn to its retracted position by means of a coil spring 25, one end of which is hooked over the end 9 and the other end of which is engaged in the portion 24 of the drawer. The out-turned 100 ears 21 of the drawer engaging the front edge of the vertical portions 5 of the guide prevent the drawer from being retracted too far into the slide, and the drawer is prevented from being withdrawn too far by 105 means of a cross bar 26 which extends through slots 27 in the sides 5 of the guide and through the side walls 19 of the money drawer. The forward ends of the slots 27 are extended upwardly as at 28 so that when the drawer is 110 withdrawn and tilted down, due to gravity, the rear end of the drawer being tilted up,

will cause the bar 26 to move upwardly in the slots 28 and thereby prevent the drawer from being retracted until it is tilted up to a substantially horizontal position.

5. A spring holder 29 for collection mail is secured to the under side of the guide and is preferably formed from a single piece of wire having a U shaped portion, the two legs of the U at their rear end being coiled to form 10 springs 30 and the wire then continued forward to form a loop to receive the securing bolts 14.

In operation the mail for collection is deposited beneath the spring holder 29 and the 15 money to pay for postage placed in the coin box. When the carrier delivers mail he inserts the same in the bottom of the box and as he removes his hand from the box, by 20 grasping the two ears 21 of the coin box, he may pull the same forward and tilt it down so that the money contained therein will drop into his palm. Then by releasing the 25 money box and tilting it slightly upwardly to the horizontal the box will automatically return to its normal position and he may then 30 remove the collection mail from its spring support. It will thus be noted that the carrier may deposit delivery mail, remove collection mail and the postage money to pay for the same in practically one movement of one hand.

I claim as my invention:

1. A money drawer for mail boxes comprising a drawer guide having transversely 35 extending flanges for attachment to the box, a drawer slidably and tiltably mounted in said guide, means having a tendency to retract the drawer to its non-delivery position, and means operated by the tilting movement of 40 the drawer to its delivery position for rendering said retracting means ineffective.

2. A money drawer for mail boxes, comprising a drawer guide for attachment within 45 the box, a money drawer horizontally slidably mounted in said guide and tiltably in said guide when projected to its forward position, means for retracting said drawer when the

same is moved to a horizontal position and means operated by the tilting of said drawer for rendering said means ineffective.

3. A money drawer for mail boxes, comprising a drawer guide having a longitudinal channel therein and having transversely extending flanges for attachment to the mail box, a money drawer slidably mounted in said channel, a coiled spring having one end connected to the rear end of said drawer and the other connected to the rear end of said channel and adapted to normally retract said drawer from a delivery position, locking 60 means moved into operative position by the downward tilting of said drawer when the drawer is projected to delivery position for locking said drawer against retraction, and means for preventing the drawer from being retracted beyond a predetermined point in said guide.

4. A money drawer for mail boxes comprising a drawer guide, a drawer slidable in said guide and tiltably therein, means for preventing the drawer from tilting until it has reached the limit of its opening movement, means tending normally to retract said drawer and means operated by the tilting movement of the drawer for rendering said 70 retracting means ineffective.

5. A money drawer for mail boxes comprising guide members, each having longitudinally extending slots therein merging at their forward ends in upwardly extending slots, a drawer operating between said guides and fingers on said drawer engaging in said slots and preventing said drawer from tilting until it has reached the limit of its forward movement, and a spring normally tending to 80 retract said drawer, the movement of said fingers in said upwardly extending slots rendering said spring ineffective.

In witness whereof, I, JESSE P. SHORT, have hereunto set my hand at Greensburg, Indiana, this 13th day of June, A. D. one thousand nine hundred and twenty seven.

JESSE P. SHORT.
